UNITED STATES PATENT OFFICE.

JAMES A. MITCHELL, OF DAYTON, OHIO.

DESIGN FOR A WIRE-STRETCHER.

SPECIFICATION forming part of Design No. 29,499, dated October 18, 1898.

Application filed August 8, 1898. Serial No. 688,110. Term of patent 7 years.

To all whom it may concern:

Be it known that I, JAMES A. MITCHELL, a citizen of the United States, residing at Dayton, in the county of Montgomery and State 5 of Ohio, have invented and produced a new and original Design for a Wire-Stretcher, of which the following is a specification, reference being had to the accompanying drawings, showing a part thereof.

Figure 1 shows a front view, and Fig. 2 a back view, of my design. Fig. 3 shows an edge view of the same. These three views are necessary to fully illustrate my design.

A is a representation of one side of my 5 wire-stretcher, showing the indented face. C is a square lug showing the center perforation or indentation. B represents the other

side of the stretcher, showing the central groove D through the same. These two parts A and B, as shown in the drawings, are joined together or united on each side of the groove, the whole having the general appearance of a ratchet-wheel connected by a cylindrical body at the center and a rectangular or square lug upon one side thereof. 20 25

Having thus described my invention, what I claim is—

The design for a wire-stretcher, as herein shown and described.

JAMES A. MITCHELL.
